CLAIM

The ornamental design for an end effector for a robot, as shown and described.

DESCRIPTION

FIG. 1 is a top perspective view of an end effector for a robot showing our new design;

FIG. 2 is a bottom perspective view thereof;

FIG. 3 is a right side elevation view thereof;

FIG. 4 is a left side elevation view thereof;

FIG. 5 is a rear elevation view thereof;

FIG. 6 is a front elevation view thereof;

FIG. 7 is a top plan view thereof;

FIG. 8 is a bottom plan view thereof;

FIG. 9 is a top perspective view of another embodiment of an end effector for a robot showing our new design;

FIG. 10 is a bottom perspective view thereof;

FIG. 11 is a right side elevation view thereof;

FIG. 12 is a left side elevation view thereof;

FIG. 13 is a rear elevation view thereof;

FIG. 14 is a front elevation view thereof;

FIG. 15 is a top plan view thereof; and,

FIG. 16 is a bottom plan view thereof.
